TELLURIAN

Filed July 10, 1928

UNITED STATES PATENT OFFICE

DAVID PHILLIPS, OF DAYTONA BEACH, FLORIDA

TELLURIAN

Application filed July 10, 1928. Serial No. 291,656.

This invention relates to that class of exhibitive or instructional astronomical devices known as tellurians and has for its object the provision in a tellurian having sun and earth spheres mounted for bodily movement of the earth relative to the sun in a path denoting the ecliptic, with means for effecting rotation of the earth sphere about an axis parallel with the axis of the ecliptic during the 10 traverse of the ecliptic circle proportioned to denote the changing of the earth's surface relatively to the sun's projected light for the different seasons, of means additionally for denoting automatically with the change of 15 seasons during traverse of the ecliptic circle, the changing areas covered by the earth's shadow, including the positions of the poles and arctic circles relatively to the sun sphere during the ecliptic traverse.

20 A further object of the invention is the provision with sun and earth spheres relatively movable in the ecliptic circle, of means providing a physical embodiment of the earth's shadow relatively to the sun and relatively to which shadow the earth rotates about an axis parallel to the axis of the ecliptic circle and at right angles to the longitudinal median line or axis of the shadow, the earth being supported with its vertical axis in line 25 with said axis of rotation and with its polar axis or axis of diurnal revolution inclined at an angle of substantially $23\frac{1}{2}$ degrees to the vertical.

The substantially right angular relation of 30 the axis of the shadow to the vertical axis of rotation of the earth sphere, with the polar axes of the latter inclined to said vertical axis at the proper angle, ensures the presentation of the appropriate earth areas to be covered by the shadow, and with the polar, equatorial and other prominent earth divisions indicated on the surface of the earth sphere, the seasonal relation of the sun and earth are forcibly and clearly presented to the student.

40 The invention is illustrated in connection with a form of educational astronomical device or tellurian of the type shown in my pending application, Serial No. 231,111, and will be more clearly apparent from the following detailed specification which is to be

read in conjunction with the accompanying drawings forming part thereof and in which:—

Figure 1 is a view in side elevation of a tellurian embodying the improvements of the 55 present invention.

Figure 2 is a longitudinal vertical section on an enlarged scale through the sun and earth spheres, the conical earth's shadow and the arms supporting the earth sphere and 60 shadow and connecting and intergearing the sun and earth spheres.

Figure 3 is a perspective detail of the conical shadow detached.

The device is supported from a suitable 65 base 1 which may, as in my application aforesaid, be superposed upon a zodiac table 2. A vertical axis stud 3 is carried by and up-stands from the base 1, its front end being threaded into a socket formed on the interior 70 of the fixed upper semispherical half 4 of a sectional hollow sun sphere. The stud 3 projects through a bore formed centrally in the lower semispherical half 5 of the sun sphere which is supported to revolve about 75 the stud 3 as an axis by means of a collar 6 fixed to the stud below the sphere section 5. An annular groove 7 encircles the exterior of the lower half 5 of the sun sphere and is designed to receive a belt or similar wrap- 80 ping connector by means of which the revolu-ble lower section of the sun sphere may be turned about the axis stud 3, which stud represents the vertical axis of the sun sphere and the axis of the ecliptic circle.

Upon the stud 3 within the interior of the hollow lower section 5 below its line of junction with the upper section 4 of the sun sphere, a fixed gear 8 is mounted. In line with this gear, the side of the lower hollow 85 section 5 is slotted at 9 (Figure 2) and the spaced inner ends of the spaced bars 10 and 11 are suitably secured in parallel to the opposite sides of the upper and lower slotted portions 9. The bars 10 and 11 extend radially outward from the lower sun section 5 in parallel, the upper bar 10 extending a substantial distance beyond the lower bar 11. At a point adjacent to the outer end of the lower bar and intermediate the ends of the

upper bar, a table 12 is positioned to overlie the latter and is provided with a vertical axis stud or shaft 13 extending downwardly through alined bores in the upper and lower bars 10 and 11. Between these two bars, a gear 14 is fixed to the stud 13, this gear corresponding in size and construction to the gear 8 within the hollow sun sphere. A chain 15 or other suitable wrapping connector extends over the gear 14 of the revoluble table axis stud 13 and wraps over the fixed gear 8 upon the fixed axis stud 3 depending from the upper fixed sun section 4. The chain will extend and be housed between the upper and lower bars 10 and 11 and will extend through the tunnel formed by the slot 9 formed in the lower and revoluble sun section 5.

Swinging movement of the arm provided by the bars 10 and 11 with the lower sun section about the vertical axis stud 3 will cause the chain connector 15 which is, of course, taut between the gears 8 and 14 to wrap over one side of the fixed gear 8 and unwrap from the other side producing a corresponding rotation of the gear 14. Since the gears 8 and 14 are identical in size, a complete revolution of the lower sun section 5 with its radially extending bars 10 and 11 will produce a complete revolution of the gear 14 and of the vertical axis shaft 13 of the table 12.

This revolution of the table represents, and, as will be seen, causes a complete revolution of a sphere representing the earth about a vertical axis parallel with the sun axis and the axis of ecliptic path, this revolution corresponding to the revolution of the earth during its annual traverse of the ecliptic.

Accordingly, an earth sphere 16 is fixedly supported over the table 12 with its vertical axis alined with the vertical axis shaft 13 of the table and with its pole axes inclined at the usual $23\frac{1}{2}$ ° angle to the vertical, the polar axes being in the line of a stud 17 fixed to and upstanding from the table 12 at the requisite angle and affording a convenient means for supporting the earth sphere from the table with its pole axes as described and with its vertical axis alined with the table axis 13.

In order to properly and visually indicate the shadow on the earth at the side opposite to the sun, I have provided a hollow conical shadow 18 supported with its longitudinal median line or axis extending in a line at right angles to the axis 13 of the earth-supporting table 12 so that the rotation of the earth with the table about its vertical axis will cause the true portions of the earth sphere to pass within and be covered by the cupped open end of the conical shadow in true proportion to and representation of the natural phenomenon.

The shadow is positioned in this proper

relation by means of eye bolts 19 having their eye portions embracing the cone of the shadow at points between its opposite ends and having their threaded shanks 20 extending through elongated slots 21 and engaged by clamping nuts 22 above and below said slots. The adjustment thus provided permits the shadow cone to be adjusted to a position in which its axis or longitudinal median line extends at the proper angle to the axis of the table shaft 13. The cupped open end of the shadow cone is positioned to embrace the half of the earth sphere at the side of its vertical axis diametrically opposite to the axis of the sun sphere. The lower edge of the shadow cone 18 will therefore impinge upon the inclined pole pin 17 and to provide clearance for this pole pin and permit the latter to rotate with the table 12 about the vertical axis of its shaft 13, the lower portion of the shadow of the shadow cone is formed with an arcuate notch 23 on a radius corresponding to the arc of movement of the abutting portion of the pole pin 17.

An indicator arm or pointer 24 extends radially from the lower sun section 5 at a point diametrically opposite to the bars 10 and 11 and coordinates with the zodiac table 2 to indicate the particular constellation and the season of the year entered by the particular portion of the earth's surface under observation and the relative positions of other portions of the earth's surface within and without its shadow at the particular point in the traverse of the ecliptic indicated by the pointer 24. One half of the earth sphere is enveloped in shadow at all times. During one spring and summer, the North pole faces the sun all the time; on the first day of summer, the entire arctic circle faces the sun. Through one fall and winter, the North pole is in the earth's shadow, the entire arctic circle being in the shadow on the first day of winter. At both equinoxes, both poles are equally in the sun and in the shadow.

The described construction therefore will clearly demonstrate to the student the seasonal aspects of the different portions of the earth sphere during its traverse of the ecliptic circle. The particular construction of the conical shadow 18 may vary within reasonably wide limits. Preferably, and as shown, it will consist of a hollow cone of aluminum.

The specific form of the invention described herein while representing a preferred embodiment thereof is intended as illustrative rather than restrictive of the invention and is subject to structural variation and adaptation within the spirit of the invention and the scope of the appended claims.

What I claim therefore and desire to secure by Letters Patent is:

1. In a device of the character described, an earth-carrying arm mounted at its inner end to swing about a vertical axis represent-

ing the axis of the ecliptic circle, a support mounted on said arm intermediate of its ends for rotation about a vertical axis parallel with the ecliptic axis, a pole arm upstanding from 5 said support at an angle to the vertical, an earth sphere mounted on said arm with its vertical axis in line with the axis of rotation of said support and with its polar axis coincident with that of said arm and inclined to 10 the vertical axis, and a conical shadow bodily mounted on said arm at the side of the earth opposite to the ecliptic axis with its longitudinal axis extending in right angular relation to the vertical earth axis and with 15 the open end enclosing that half of the earth sphere diametrically opposite to the ecliptic axis, the lower edge of said open end being notched to embrace said pole arm and position the edge of the open end of said shadow 20 in the vertical axis of the earth sphere.

2. In a device of the character described, an earth-carrying arm mounted at its inner end to swing about a fixed vertical axis stud representing the axis of the ecliptic circle, an 25 earth support having a vertical axis stud mounted on said arm intermediate of its ends in parallel with said ecliptic axis, having a pole pin upstanding therefrom at an angle to the vertical, an earth sphere positioned on 30 said pin bodily to rotate therewith with its vertical axis in line with the axis of rotation of the axis stud of the support and with its polar axis coincident with that of said pin and inclined to the vertical, a gear mounted on 35 said fixed vertical axis stud, a similar gear mounted upon the rotatable axis stud of the earth support, a wrapping connector encircling said gears to effect rotation of the earth support through swinging movement of the 40 earth-carrying arm about the ecliptic axis stud, a conical shadow positioned at the side of the earth sphere diametrically opposite to the ecliptic axis stud and having the lower edge of its open end notched to embrace said 45 pole pin and position the edge of the open end of the shadow in the vertical axis of the earth sphere to envelop that half of the earth sphere at the opposite side of said stud, and spaced supports upstanding from said 50 arm and vertically adjustable to support said conical shadow with its longitudinal median line at right angles to the vertical axis of said earth support.

3. In a device of the character described, 55 a hollow sectional spherical sun body having a fixed semi-spherical section mounting a fixed axis stud and a complemental revoluble semi-spherical section enclosing and journaling on a portion of said stud, a gear fixed 60 to the stud within the revoluble semi-spherical portion, a slot formed in the peripheral surface of said portion in alignment with said gear, spaced bars rigidly secured to the opposite side walls of said slot and extending 65 radially outward from the sun sphere axis in

parallel horizontal planes with the upper bar extending beyond the end of the lower bar, an earth-supporting table having an axis stud journaling in alined bores in said bars at the end of the lower bar to rotate about 70 an axis parallel with the sun axis, a gear mounted on said axis stud between said bars, a wrapping connector encircling said fixed sun stud gear and the gear on the rotatable axis stud of the earth supporting table, an earth supported on said table with its vertical axis alined with the axis of the table stud and with its polar axes inclined to the vertical, and a hollow conical earth shadow supported 75 from the extended end of the upper radial bar and positioned with its open cupped end overlying that half of the earth sphere diametrically opposite the axis of the sun sphere, with the longitudinal axis of the conical shadow extending at right angles to the lines 80 of the axis stud of the earth supporting table.

Signed at Durham, in the county of Durham and State of North Carolina, this 7th day of July, A. D. 1928.
